UNITED STATES PATENT OFFICE

120,758

DESIGN FOR A HANDBAG OR SIMILAR ARTICLE

Florence Kuhlman, New York, N. Y., assignor to Robert Appel, New York, N. Y.

Application April 22, 1940, Serial No. 91,838

Term of patent 3½ years

To all whom it may concern:

Be it known that I, Florence Kuhlman, a citizen of the United States, residing at New York city, in the county and State of New York, have invented a new, original, and ornamental Design for a Handbag or Similar Article, of which the following is a specification, reference being had to the accompanying drawing, forming part thereof.

The figure is a perspective view of a handbag or similar article, showing my new design.

The side and end not shown on the drawing are substantially like the side and end shown.

The characteristic features of the design reside in the ornamentation on the handbag.

I claim:

The ornamental design for a handbag or similar article, substantially as shown and described.

FLORENCE KUHLMAN.
